CLAIM

The ornamental design for an optical module, as shown and described.

DESCRIPTION

FIG. 1 is a front perspective view of an optical module according to an embodiment of the present design.

FIG. 2 is a rear perspective view of the optical module of FIG. 1.

FIG. 3 is a front view the optical module of FIG. 1.

FIG. 4 is a back view of the optical module of FIG. 1.

FIG. 5 is a left side view of the optical module of FIG. 1.

FIG. 6 is a right side view of the optical module of FIG. 1.

FIG. 7 is a top view of the optical module of FIG. 1; and,

FIG. 8 is a bottom view of the optical module of FIG. 1.

The broken lines shown in the drawings depict unclaimed environmental structure and form no part of the claimed design.
